UNITED STATES PATENT OFFICE.

GEORGE W. PETER, OF ST. LOUIS, MISSOURI.

DRAFT-EQUALIZER.

SPECIFICATION forming part of Letters Patent No. 759,466, dated May 10, 1904.

Application filed February 11, 1904. Serial No. 193,067. (No model.)

To all whom it may concern:

Be it known that I, GEORGE W. PETER, a citizen of the United States, residing at St. Louis, Missouri, have invented a new and useful Equalizer, of which the following is a specification.

This invention relates to equalizers or treble-trees; and it consists of the novel construction, combination, and arrangement of parts herein shown, described, and claimed.

The object of the invention is to provide an equalizer comprising a central member geared to the draft members at each side, whereby differential movement proportioned in scope inversely to the power is imparted by one draft member to the other whenever the horse or team at either side draws ahead or lags behind, the construction and arrangement being such as to maintain uniform leverage for both draft members throughout their varying movements, so that no advantage is gained by the horse or team ahead, no disadvantage thrown to those in the rear. This enables the horse or team behind to gain upon those in front without drawing more than the natural or predetermined proportion of the load.

Figure 1 is a plan view of the equalizer. Fig. 2 is a front view with the swingtrees omitted.

30 The member 1 is attached rigidly by means of braces, as shown, or otherwise, if preferred, to the vehicle, and at its center is mounted a gear-wheel 2 upon an axial pin 3.

The swingtree draft member or lever 4 is pivoted to the member 1 by the pin 5 and has a gear-segment 6 attached to its inner end, which segment is in constant mesh with the wheel 2. The method of attaching the segment 6 to the lever 4 is immaterial; but in the form shown the end of the lever extends into a socket in the segment and is fastened therein by bolts. A shoulder 7 is formed at each side of the sector, and when the lever 4 swings on its pivot the shoulder 7 eventually strikes one of the teeth on the wheel 2, and being of less depth than that required to receive a tooth further movement of the lever is prevented. This position of the lever is shown by dotted lines in Fig. 1, the said lever there being at 40 the rear as far as it may move.

Near the opposite end of the member 1 from the lever 4 there is mounted a lever 8, to the outer end of which the doubletree is attached, as shown. The lever 8 is pivoted upon the member 1 by a bolt or pin 9, and a gear-segment 10 is attached to the inner end of said lever, said segment being meshed constantly with the wheel 2. The connection of the segment 10 with the lever may be the same as that described for the segment 6 and lever 4, or any other preferred method of attachment may be used. Shoulders 11, similar in construction and function to the shoulders 7, are formed on the sides of the segment 10, as shown in Fig. 1.

55 The segments 6 and 10 must necessarily be retained in constant mesh with the wheel 2, as heretofore stated, and for holding them in such position I provide a retaining-strip 12, lying across the wheel 2, held thereon by the axial bolt 3 and having its ends overlying the segments 6 and 10, so that they cannot be raised out of mesh with the wheel by depression of the outer ends of their respective levers. The strip 12 is further retained in position by the bolt or pin 5, so that turning or 60 displacement thereof is prevented.

To assist and coöperate with the shoulders 7 and 11 in preventing too far movement on the part of the levers 4 and 8, I provide an auxiliary lock to stop rotation of the wheel 2, or rather to define limits within which the wheel can turn. This auxiliary lock consists of two pins, projections, or lugs, such as 13, diametrically opposite on the upper face of 65 the wheel 2 and adapted to engage or strike against the edges of the strip 12 at the time the shoulders 7 and 11 engage the wheel 2, and thereby remove from the shoulders and wheel-teeth some of the strain incidental to 70 holding the levers.

The movement of the two levers on their pivots is differential, determined by the relative distance of their pivots from the wheel and inversely to the power applied. This differential movement of the levers does not inure to the advantage of either horse or team, because the same power applied to either lever will produce the same result or effect irrespective of the position of the lever, or, 75 80 85 90 95 100

in other words, it requires just or approximately the same power to move either lever to turn the wheel in one position as in any other. Therefore the equality of draft as distributed among the horses will be effectively maintained irrespective of accidental displacement of the draft-levers from their alined position at the start.

I claim—

- 10 1. An equalizer comprising a main supporting member, two draft-levers pivoted thereon, gear-segments attached to the inner ends of the draft-levers, a gear-wheel interposed between, and meshed with, said segments, a retaining-strip overlying the wheel and segments, projections on the upper face of the wheel to define the scope of rotation of the wheel, and shoulders on the segments to co-operate with the projections, substantially as specified.
- 15 2. In an equalizer, a support, two draft-levers pivoted thereon, a gear-segment on the inner end of each lever, an integral shoulder on each edge of each of said segments, said shoulders being of less depth than that required to receive a full tooth equal to the segment-teeth, a wheel on the support in mesh

with the segments, a retaining-strip removably fastened over said wheel and projecting over the segments, and two projections 13 on 30 said wheel, one of said projections being on each side of the retaining-strip, substantially as specified.

3. The combination with the draft-levers 4 and 8, the gear-segments 7 and 10 attached to 35 said levers, and the gear-wheel 2 in mesh with the segments, all of said devices being mounted upon a suitable support attached to the vehicle or machine, of a retaining-strip extending across the wheel and projecting over the 40 segments, means for holding said strip firmly in position, a pin or projection rigid with the wheel at each side of said strip and adapted to strike against the edges thereof to stop rotation of the wheel, and co-operating stops on 45 the segments adapted to act against the teeth of the wheel, substantially as specified.

In testimony whereof I have signed my name to this specification in the presence of two subscribing witnesses.

GEORGE W. PETER.
